UNITED STATES PATENT OFFICE.

BRICE W. HAVERFIELD, OF CHICAGO, ILLINOIS.

DESIGN FOR A MERCHANTISE-DISPLAY DESK.

Application filed June 19, 1929. Serial No. 31,765. Term of patent 7 years.

To all whom it may concern:

Be it known that I, BRICE W. HAVERFIELD, a citizen of the United States, residing in Chicago, in the county of Cook and State of Illinois, have invented a new, original, and ornamental Design for a Merchandise-Display Desk, of which the following is a specification, reference being had to the accompanying drawings, forming a part thereof, in which:

I claim:

The ornamental design for a merchandise display desk as shown.

BRICE W. HAVERFIELD.
